(57) **CLAIM**

The ornamental design for an automobile, as shown and described.

DESCRIPTION

FIG. 1 is a perspective view of an automobile showing our new design;

FIG. 2 is a rear perspective view thereof;

FIG. 3 is a Front View thereof;

FIG. 4 is a Rear View thereof;

FIG. 5 is a Left Side View thereof;

FIG. 6 is a Right Side View thereof; and,

FIG. 7 is a Top View thereof.

The broken lines in the drawings shown represent portions of the automobile that form no part of the claimed design.
